UNITED STATES PATENT OFFICE.

WALTER SHANLEY ROBERTSON, OF PHILADELPHIA, PENNSYLVANIA, ASSIGNOR TO
THE CHAS. H. ELLIOTT COMPANY, OF PHILADELPHIA, PENNSYLVANIA.

DESIGN FOR A RING.

Application filed November 20, 1922. Serial No. 4,341. Term of patent 3½ years.

To all whom it may concern:

Be it known that I, WALTER SHANLEY ROBERTSON, a citizen of the United States, residing at Philadelphia, in the county of Philadelphia and State of Pennsylvania, have invented a new, original, and ornamental Design for Rings, of which the following is a specification, reference being had to the accompanying drawing, forming part thereof.

The figure is a plan view of the top of the ring showing the new design, the ring being shown in dotted lines.

I claim:

The ornamental design for a ring, as shown.

WALTER SHANLEY ROBERTSON.
